UNITED STATES PATENT OFFICE.

ALBERT W. MYERS AND ROBERT R. FITZ GERALD, OF OTTAWA, ONTARIO, CANADA,
ASSIGNORS TO ALBERT W. MYERS, OF OTTAWA, ONTARIO, CANADA.

AERIAL MACHINE.

1,258,356.

Specification of Letters Patent. Patented Mar. 5, 1918.

Application filed August 29, 1917. Serial No. 188,853.

To all whom it may concern:

Be it known that we, ALBERT W. MYERS and ROBERT R. FITZ GERALD, citizens of the Dominion of Canada, residing at Ottawa, in the county of Carleton and Province of Ontario, Canada, have invented certain new and useful Improvements in Aerial Machines, of which the following is a specification.

10 This invention relates to means, attachable to aeroplanes, so as to act as a safety parachute should the aeroplane be disabled.

The main object of our invention is to provide a device which can be easily attached to 15 the present design of aerial machines.

15 A further object is to provide a device which will have very little resistance against the forward motion of the aerial craft on which it is mounted.

20 A further object is to provide a device which can be easily and quickly thrown into operation.

With these and other objects in view, the 25 invention consists in the construction, combination and arrangement of parts as will be hereinafter fully described, illustrated in the accompanying drawings, and pointed out in the claim hereunto appended.

Figure 1 shows a perspective side view of 30 our invention in closed position. Fig. 2 shows a view of the same in open position. Fig. 3 shows an enlarged sectional view of the operating mechanism.

Referring to the drawings like numerals 35 designate like parts in the various drawings.

4 indicates a portion of the aeroplane, preferably the top, on which our invention is adapted to be mounted.

5 is a cylindrical vertical positioned member having a flanged lower end through 40 which suitable fastening means attach it to the portion of the aeroplane 4. Centrally inside this member is an upright pipe or rod 6 having a small notch 7 on its rear side. In 45 the lower portion of member 5, we provide an annular ring 8 securely attached to the inner side of said member. 9 is a compressible coil spring having a plate secured at its top and bottom, the bottom plate adapted 50 to rest on the annular ring 8. The section below this annular ring 8 is adapted to receive a coil of rope or cable 10, the use of which rope or cable will be hereinafter explained.

55 11 is a parachute of any particular design

having an annular keeper 12 which keeps the free ends in closed position. This keeper is positioned on the center bar 14 and is limited in operation by the pin 15.

A ferrule 16 fits over the end of the center 60 bar 14. This ferrule is cut in sections, the other section 16^b being adapted to stay in an upright position on the upright 6. The two parts are hingedly connected at 17 and are tensioned by the springs 18, to position 65 themselves in parallel relationship when free to do so. 19 is a spring attached to the rear of part 16, and its free end is adapted to engage in the notch 7 when the part 16^b is pressed down on the upright 6. 20 is a 70 ring slidably positioned around the lower end of part 16^b. Arms 21 connect this ring 20 to the hinge-portion 17, the connection to portion 17 being so as to act as an eccentric.

75 From this description and the accompanying drawings, it will be seen that when the parachute is in parallel relationship to the aeroplane, the ring 20 is pressed down so as to allow the end of the spring 19 to engage in the notch 7 and thus securely hold this 80 end of the device down. When the top end of the parachute is freed the tension springs 18 will draw it so as to bring the parts 16 and 16^b in parallel relationship. In doing this the hinge-portion 17 in turning pulls 85 the ring 20 upwardly. The side of the ring under the spring 19 will press out on it, thus disengaging the end of spring 19 from notch 7. The compressed coil spring 9 will now 90 shoot the parachute into the air above all the working parts of the aeroplane. The parachute has suitable springs 22 or other means to throw the parachute open. The rope or cable 10 is attached at 23 and extends down to the lower portion of the cylindrical member 5 as hereinbefore mentioned. 95 A small check rope 24 is attached to the cable or rope 10 and to the keeper 12 so that when the rope or cable is drawn in tight, this keeper 12 is drawn down, thus freeing 100 the parachute for opening.

25 is a cylindrical member mounted at a suitable position on the plane 4. 26 is a coil spring having a bearing secured at its top. This coil spring is adaptable for compressing 105 into the cylindrical member 25. The bearing is adapted to receive the upper end of the parachute 11. 27 is a hingedly connected trip-member having one end adapted to engage the ends of the parachute 11 and 110

the other end spring-tensioned by the spring 28. 29 is a trip-rope attached to the spring-tension of the trip-member 27 and extending down to a suitable position where the operator can easily pull the same.

From the foregoing it is thought that the construction of our invention will be clearly understood, and therefore a more extended explanation has been omitted.

10 What we claim as new, is,—

A safety attachment for aerial machines consisting of a parachute, a trip-member adapted to engage at the free end of the parachute, means for disengaging said trip-member, a means for holding the other end

of said parachute, a means for releasing said holding means when said parachute is in a vertical position, a means for releasing the opening of said parachute, an attaching means between said parachute and said air 20 craft, and a means for shooting said parachute into the air.

In testimony whereof we affix our signatures in the presence of two witnesses.

ALBERT W. MYERS.
ROBERT R. FITZ GERALD.
